[54]	APPARATUS FOR COILING LAMP FILAMENT SUPPORTS 4 Claims, 11 Drawing Figs.			ABSTRACT: The apparatus comprises a coiling spindle having an axial passageway for periodic movement therethrough of a filament containing a mandrel. The free end of a supply of support wire is temporarily clamped in a slot at the periphery of the spindle which has a die at its end face such that, upon rotation of the spindle, the wire is coiled first around the periphery thereof and then around a generally spiral track in said end face and then down between turns of the filament. A reversing finger member then urges the wire back in the opposite direction to form a locking overwind which is then severed from the supply of support wire. A pressure finger member is then pressed against the outer helical turns on the spindle to partially set the turns and minimize opening or offsetting thereof relative to the filament.

APPARATUS FOR COILING LAMP FILAMENT SUPPORTS

BACKGROUND OF THE INVENTION

Support members of the type described above have been used with good results in a now well-known tungsten-halogen-type of lamp which comprises an elongated tubular envelope having an axially extending filament which is supported from the envelope wall by engagement therewith of the helical outer turns of such support members located at spaced points along the filament. Such supports, and a coiling spindle or mandrel for winding and installing these supports on the filament, are shown in U.S. Pat. No. 3,168,670 to V. C. Levand, Jr. However, that particular form of spindle requires that the support wire be cut at three points which results in a wastage of wire which is generally made of tungsten.

Other forms of support-forming and -installing apparatus have been proposed which require two cuts or only a single cut. However, in those devices the opening for the filament coil is located eccentrically in the coiling spindle and reliance is placed on the smaller filament-engaging turns shifting to a concentric position relative to the larger outer turns upon severing of the finished support from the supply of support wire.

SUMMARY OF THE INVENTION

It is an object of this invention to provide apparatus for coiling a support wire member of the type referred to above which require but a single cut, and will result in a minimum of spring back and very little, if any, offsetting of the small inner turns relative to the large outer turn or turns. To that end, the improved apparatus winds the larger and small turns concentrically and provides for setting the turns in a manner to effectively overcome undue spring back or offsetting of the coil turns.

BRIEF DESCRIPTION OF THE DRAWINGS

FIG. 1 is a fragmentary perspective view, on an enlarged scale, of one end of an incandescent lamp having filament supports made by apparatus according to the invention;

FIGS. 2 and 3 are side and front end elevations, respectively, and on a reduced scale, of apparatus comprising the invention;

FIG. 4 is a vertical section, on an enlarged scale, of a winding head chuck assembly including coiling spindle and associated filament-holding and support-wire-locking elements;

FIG. 5 is a fragmentary perspective view, on an enlarged scale, of the front ends of the coiling spindle and the associated nosepiece of a locking chuck in their relative angular positions for receiving the free end of a support wire;

FIG. 6 is a fragmentary side view of the coiling spindle with the nosepiece removed for greater clarity;

FIGS. 7 and 8 are fragmentary front end and side views, respectively, of the nosepiece;

FIGS. 9 and 10 are fragmentary front views of the coiling spindle and nosepiece at the start and end, respectively, of the support wire coiling process; and

FIG. 11 is a fragmentary perspective view of the coiling spindle, nosepiece and pressure finger at the end of the coiling operation.

DESCRIPTION OF THE PREFERRED EMBODIMENT

Referring to FIG. 1, there is shown one end of a tungsten-halogen-type lamp comprising an envelope 1 of quartz or other transparent vitreous material of high softening point, and containing an elongated helically coiled tungsten filament 2 having a straightened end portion extending into a pinch seal 3 and connected to an extremely thin foliated portion 4 of a lead-in wire 5. The coiled filament 2 is supported substantially in the axis of the tubular envelope 1 by spaced coiled support wire members 6 which are formed and secured thereto in ac-

cordance with the present invention. The envelope 1 may, in a typical case, be of about three-eighths or one-half inch outside diameter.

Referring particularly to FIGS. 4 and 2, the assembly of helically coiled filament 2 on its mandrel 7 is inserted into a winding head chuck assembly 8 which is carried by a hollow shaft 9 which is journaled for rotation in a pair of uprights 10 and 11 on a base member 12. The chuck assembly 8 is rotated by a pinion 13 which is fastened to shaft 9 and which is driven by a large gear 14 which is mounted on a drive shaft 15 which is also journaled in uprights 10 and 11. For the forming of each filament support 6, the shaft 15 may be rotated a predetermined controlled amount, for example a single revolution, by a well-known electric motor and timer assembly (not shown).

The filament coil 2 extends through an axial opening or passageway 16 (FIG. 5) in a spindle 17 and is locked in position during forming of a support 6, by a collet 18 (FIG. 4). The spring finger portions of the collet are held normally closed by being pressed against the tapered end 19 of the enlarged axial opening 20 by a spring-loaded tube 21 which extends through the interior of shaft 9. The spring 22 acting on tube 21 may be, as illustrated in FIG. 2, anchored at one end to upright 10 and attached at its other end to a lever 23 which is pivoted on a pin in an arm 24 attached to upright 10. The lever 23 is suitably connected to tube 21 to normally urge it to the right in FIGS. 2 and 4, and may be provided with a handle 25 to move tube 21 to the left and thereby release the grip of collet 18 on filament 2 when it is desired to move the filament forward periodically for attachment of additional support members 6 thereto.

The winding head chuck assembly 8 further includes a locking chuck assembly 26 which includes a cylindrical sleeve portion 27 surrounding the enlarged end of shaft 9, and a nosepiece 28 fastened to the front end thereof by bolts 29. The nosepiece 28 has an axial opening 30 which closely fits the peripheral surface of the reduced end 31 (FIGS. 4, 5 and 6) of the spindle 17. The nosepiece 28 further has an annular front end face 32 (FIGS. 4, 5, 7 and 8) of helical pitch with a sharp shoulder 33 defining the beginning and the end of the helical surface. The shoulder 33 extends across the annular end face 32 (FIGS. 5 and 7) at an angle such that its inner end is at the axial opening 30 and adjacent to the back end of a generally tangential slot 34 (FIGS. 5, 6 and 9) in the peripheral surface 31 of the spindle 17, at a given rotational position of the nosepiece 28 of the locking chuck 26.

The spindle 17 is locked to the shaft 9 by a setscrew 35 (FIG. 4) which has a smooth unthreaded head which is located in an arcuate circumferential slot 36 in the sleeve portion 27 of locking chuck 26. Thereby, the spindle 17 is at all times locked to the shaft 9 in predetermined axial relation to the nosepiece 28, and the locking chuck 26 also rotates with the shaft 9 when the head of the setscrew 35 is held at one end of the arcuate slot 36 by virtue of the action of a torsion spring 37 which has one end 38 anchored in the sleeve 27, and the other end 39 held against the shoulder 40 of a reduced diameter portion of a collar 41 which is locked to shaft 9 by a setscrew 42. The arcuate slot 36 is of short angular extent such that the locking chuck 26 can be rotated clockwise, as seen in FIG. 9, sufficiently so that the shoulder 33 on nosepiece 28 makes an acute angle with, and exposes, the slot 34 for reception of the end of a length of support wire 43 which is pushed along said shoulder 33 into the slot 34, after which the chuck 26 is released and rotates counterclockwise so that the inner end of the shoulder 33 clamps the end of the wire 43 in the slot 34 to begin the support-wire-forming cycle.

The supply of support wire 43 (FIG. 2) is carried on a spool 44 which is mounted for rotation about a shaft 45 carried by a third upright 46. The spool is preferably provided with a conventional brake which applies tension to the wire 43 during winding of a support, and prevents overrunning of the spool when rotation of spindle 17 is stopped. The wire 43 passes through an aperture in a rodlike support member 47 which is mounted on upright 11.

As indicated above, to start the formation and installation of a support wire member 6, the locking chuck 26 is rotated relative to spindle 17 by grasping the sleeve portion 27 and turning it clockwise (FIG. 9) until the end of the arcuate slot 36 (FIGS. 2 and 4) engages the head of the setscrew 35, at which time the inner end of the shoulder 33 on the face of nosepiece 28 (FIGS. 5 and 9) is at the end of the slot 34. Then the end of wire 43 extending from spool 44 through support 47, is placed against the shoulder 33 (FIG. 9) and is slid along the shoulder into the end of slot 34. The locking chuck 26 is then released to permit the torsion spring 37 to rotate it relative to the spindle 17 so that the inner end of shoulder 33 rotates in a direction to cover over the slot 34 until it strikes the wire 43 and clamps it firmly in said slot 34.

The drive shaft 15 and gear 14 are then started into rotation to, in turn, rotate pinion 13 and shaft 9 and winding head chuck assembly 8. The rotation of spindle 17, with the cooperation of the helical end face 32 of the nosepiece 28 causes the wire 43 to be coiled helically around the surface 31 of spindle 17 for about one and a half turns 47' (FIGS. 10 and 11) after which the wire begins to ride down on a spiral track portion 48 (FIGS. 5, 9 and 10) of a die at the end face of the spindle to form the spiral portion 48' of the support. The said spiral track portion 48 is interrupted by a straight chordal section 49 to form a straight wire section 49' with sharp bends 50 at the ends thereof. The wire then makes a sharp bend at 51 as it passes around a corresponding sharp bend 52 in the die track as it turns abruptly radially inward at 53.

The support wire then comes down into engagement with the filament mandrel 7 between an adjacent pair of turns of the filament coil 2 (FIG. 11) to form several small diameter turns 54 which are concentric with and between several turns of the filament coil 2. The direction of coiling is then abruptly reversed to form a locking overwind 55 which may consist of one or more turns of large pitch.

The reversal in coiling direction to form the locking overwind 55 is performed by a finger member 56 (FIGS. 2 and 3) on the end of a lever 57 which is pivotally mounted on a pin 58 in a bracket 59 which is supported from the upright 11. A roller 60 at the lower end of said lever 57 rides on an annular face cam surface 61 (FIG. 3) on a cylindrical member 61' mounted on the end of drive shaft 15. The roller 60 is held against the cam surface 61 by a spring 62 which is connected at one end to the pin 63 carrying roller 60, said spring 62 being anchored at its other end to upright 11.

As seen in FIG. 2, the reversing finger 56 is normally located adjacent and to the front of the length of support wire 43 and adjacent the coiling spindle 17. The said finger 56 is abruptly moved to the left in FIG. 2 and across the path of the wire 43 to effect the formation of the reverse locking turn 55 (FIG. 11) by a pivotal movement of a lever 57 as the roller 63 is moved quickly and briefly to the right in FIG. 2 when it is engaged by a steeply inclined rise portion (not shown) on the cam surface 61. The rise portion is of very short extent and is followed by a steeply declining drop portion which quickly returns the finger 56 to its original position. Upon completion of this movement, the support 6 is completely formed, and the wire 43 is cut by the operator close to the filament 2 at the end of the overwind 55 as indicated in FIG. 10.

As illustrated herein the large drive gear makes one complete revolution while the pinion gear 13 may be proportioned to make about six or seven revolutions to form the complete support wire member 6.

While the bending operations required to form the straight chordal section 49' of the support 6 reduce materially the amount of unwinding and uncontrolled spring back occurring in the support 6 when it is removed from the spindle 17, a further step is introduced according to the invention to control the final form thereof. This final step comprises pushing the pressure finger member 64 (FIGS. 2, 3, 10 and 11), which is slidable longitudinally in sleeve 65 on the upright 46, upward against the end face of the spindle 17 and the larger helical turns 47'. The upper end of the finger member 64 (FIG.

11) has a flat surface 64' matching the end of the nosepiece 28 and a curved surface 66 (FIGS. 10 and 11) matching the outer helical turns 47' of the support 6, and when forced thereagainst will wedge in place so as to be supported thereat. 5 As seen in FIG. 11, the pressure finger 64 is moved upward into place by pushing against the enlarged head 67 (FIG. 3) at its lower end. The end of support 6 is next released from behind the locking chuck 26 by a clockwise (FIG. 3) rotation of the chuck 26, and the pressure finger member 64 is pulled very slightly away from the spindle 17. The result of these operations is to free the outer turns 47' of the support 6 so that the spring back thereof unwinds one-half to three-fourths of a turn but restricts the turns 47' to the confined space developing between the curved upper end 66 of the pressure finger member 64 and the reduced end 31 of the spindle 17. Accordingly, the turns 47' do not enlarge greatly during the spring back or relaxing of the support 6, and the small diameter and locking turns 54 and 55, respectively, of the support 6 and the filament coil 2 remain in on center or concentric to the large turns 47'.

After the pressure finger member 64 has been completely lowered, the filament coil holding collet 18 is opened by movement of the handle 25 to the left in FIG. 2, and the filament coil 2 is advanced to the right (FIGS. 2 and 11) for forming and attachment of the next support.

The supports may be spaced evenly by pulling the filament assembly out far enough so that the last completed support is opposite an upright pointer or marker member 68 (FIG. 2) which is mounted on a rod 69 supported from upright 11. If desired, a second marker 70 may be provided for sighting a pair of supports.

I claim:

1. Apparatus for producing, from a supply source of resilient wire, a continuous coil support for an elongated filament which is helically coiled about a mandrel, comprising a spindle having an axial passageway therethrough for the longitudinal movement of said filament and mandrel, a die at the end of said spindle having a generally spiral track on its face leading from its peripheral edge and terminating in a generally radial track leading toward toward the said axial passageway, and means to temporarily grip an end of a length of wire at the peripheral surface of said spindle near its edge, drive means carried by said apparatus and operable to cause rotation of said spindle and its die to cause the wire to coil around the periphery of the die and to then follow the spiral track and then the radial track down upon the mandrel between turns of the filament coil for several turns along said mandrel, means for reversing the direction of coiling the support wire over the same portion as is coiled about the mandrel to form a locking overwind, and a pressure finger means mounted for movement toward the end of said spindle and having an arcuate face engageable with portions of the helical turns on the periphery of the spindle to partially set the turns and minimize opening or offsetting thereof.

2. Apparatus as set forth in claim 1 wherein a portion of the said spiral track is interrupted by a straight chordal section to form a corresponding straight wire section with sharp bends in the wire at the ends of said straight section.

3. Apparatus as set forth in claim 1 wherein the means to temporarily grip an end of a length of wire at the peripheral surface of said spindle near its edge comprises a generally tangential slot in said peripheral surface, and a locking chuck member including a nosepiece surrounding said spindle and rotatable relative thereto and having an axial opening which makes a close fit with said peripheral surface of the spindle, said nosepiece having an annular end face of helical pitch with a sharp shoulder defining the beginning and the end of the helical surface, said shoulder extending across said annular end face at an angle such that its inner end is at the said axial opening and adjacent the back end of said tangential slot at a given rotational position of said nosepiece, and the length of the shoulder makes an acute angle with the length of the tangential slot so that the slot is open for receipt of a free end of

the resilient wire advanced along said shoulder and into the end of said slot, and means resiliently urging said nosepiece for rotation relative to the spindle to a clamping position wherein said inner end of said shoulder moves along and over said slot until it engages said wire and clamps it in said slot.

4. Apparatus as set forth in claim 1 wherein the means for reversing the direction of coiling the support wire to form a locking overwind comprises a reversing finger member, means

mounting said reversing finger member for pivotal movement and with an end portion normally located adjacent and to the front of the length of support wire and adjacent the coiling spindle, and means operable at a predetermined instant to pivot said finger rearwardly toward the support wire and across the path thereof to reverse its coiling direction.
